UNITED STATES PATENT OFFICE

2,426,198

ELECTRON DISCHARGE TUBE FOR ULTRA HIGH FREQUENCIES

Frank Douglas Goodechild and Willem Harry Wolsey, London W. C. 2, England, assignors to Standard Telephones and Cables Limited, London, England, a British company

Application September 9, 1942, Serial No. 457,791
In Great Britain October 24, 1941

6 Claims. (Cl. 250—27.5)

1

This invention relates to improvements in electron discharge tubes for ultra high frequencies of the type disclosed in United States application Serial No. 445,509.

The tube disclosed in the above application consists of a bulb having a copper disc sealed in the middle, a stem carrying the grid and cathode sealed at one end and another stem carrying the anode sealed at the opposite end. When working in the 10 cm. range there are certain limitations of the tube, and the present invention has for its main object to provide an improved construction in which these limitations are avoided by ensuring that the current path from the centre of the grid wires to the screening disc is as short and direct as possible, and thus the contact springs providing contact between the grid and the screening disc, which have been found to be a source of loss when working in this range, are dispensed with. Furthermore, the connection to the anode must be a continuous surface of metal, and thus the thimble type of anode which was sealed into the stem by the Housekeeper type seal has been replaced by a tubular anode as will be hereinafter described.

Accordingly the present invention provides a tube of the above type in which the grid is mechanically connected to the screening disc to provide intimate electrical contact therewith, whereby the current path from the centre of the grid wires to the screening disc is as short and direct as possible.

The invention also provides a tube of the above type in which the anode comprises a metal tube sealed into the stem and projecting outside the envelope to provide a direct electrical connection to the anode, which may be formed as a specially-shaped block which is secured in the end of the tube in a vacuum-tight manner.

The invention will be better understood by reference to the accompanying drawings, in which:

Fig. 1 is a sectional view of the improved tube;

Fig. 2 is an exploded view thereof;

Fig. 3 shows a preferred construction of the anode;

Fig. 4 shows a detail of Fig. 3;

Figs. 5 and 6 show respectively a plan view of the stem which supports the cathode and grid structure, having a coaxial pair of conductors.

In these drawings, 1 and 2 represent the cylindrical glass envelope portions, and 3 the copper screening disc which is sealed between them and which extends well beyond the glass envelope portions to form an effective screen between the

2

two halves of the tube, and also to provide a mounting device for connecting the tube directly in the grid circuit. The center of the disc is provided with an aperture 4 to accommodate the grid 5 which is constructed as follows. A grid unit is formed by taking a normally-wound grid made, for example, by the notch and swage method of 250 turns per inch of 0.001 inch tungsten wire wound on two nickel support rods 6. The grid wires on one side are cut away and the half grid so formed is then brazed on to a square of thick nickel or molybdenum sheet 7, which is apertured at 8 to provide the grid opening, and which is provided with four locking and fixing holes 9 by which it is supported at four points on the pillars 10 provided on the special four-pillar stem 11. The cathode 12 is also supported on this stem and as shown consists of a tubular member supported at its middle by a single wire support 13.

In assembling the valve a bulb having the screening disc 3 sealed at the centre is taken and the stem 11 is pushed in through one end. The four pillars 10 protruding through the holes 9 in the grid plate 7 then pass through corresponding holes 14 in the screening disc 3 and are secured by collars 15 on the opposite side, the welding electrodes for securing the collars being passed into the open end of the envelope portion 2. This arrangement ensures good electrical contact between the grid unit and the copper screening disc. Two of the pillars 10 also carry a mica bridge piece 16 which is apertured at 17 and forms an anode guide as will be hereinafter described. This bridge piece is secured to the pillars after the connection between the grid unit and the screening disc previously described has been completed.

For the anode, a new type of stem has been developed which consists of glass moulded to the outside of a thin-wall copper tube 18. The anode proper consists of a block 19 secured by hard soldering into the inner end of the tube 18 and forming a vacuum-tight joint therewith. As shown, the anode is rectangular in shape and is provided with shoulder pieces 20 which co-operate with the mica bridge piece 16 previously described, and which ensures accurate spacing between the anode and grid, when the anode stem is sealed into the envelope portion 2. It will be seen that with this construction a direct electrical connection is made with the anode through the anode stem 18 which projects beyond the envelope of the tube.

In the improved construction of anode shown in Fig. 3, a rod 21 of copper or other metal shown

also in Fig. 4, is inserted into the tube 18 and is secured rigidly to the block 19 in any suitable way, but preferably by means of a screw 22, as shown. The rod 21 is preferably made a snug fit in the tube 18, but its diameter should preferably be slightly reduced at 23, in the neighbourhood of the seal, in order to prevent the seal from being cracked by the expansion of the rod when the anode becomes heated. The rod 21 may be provided with a screwdriver slot as shown at 24.

It will be seen that with this arrangement, very good thermal contact is made with the block 19, which is the anode proper of the discharge tube, so that the heat is much more quickly conducted away than by the rather thin copper tube alone. When working in the 10 cm. range for example it is often necessary or desirable to bring the wave energy to and from the tube by means of coaxial conductors. In order that this may be efficiently done, a coaxial conductor should be brought inside the tube and as close as possible to the cathode. The construction shown in Figures 5 and 6 embodies this feature.

Referring to Figures 5 and 6, through the centre of the stem 11 is sealed a tube 25, preferably of copper, and inside the tube is sealed a rod or wire conductor 26 by means of a glass bead 27, which may be at the upper end, as shown, or elsewhere. The tube 25 and the conductor 26 constitute a coaxial conductor system which extends inside the discharge tube when the stem 11 is sealed into the bulb, all the joints being vacuum-tight.

What is claimed is:

1. An electron discharge tube comprising an envelope, an apertured metal screening plate extending transversely across said envelope and sealed through the walls thereof to divide said envelope into two portions, an anode in one portion and a cathode in the other portion, the said cathode being mounted on a stem carrying a plurality of pillars, a grid element comprising grid wires secured to an apertured metal plate, said plate being mounted on said pillars, and means on said pillars securing said metal plate to said metal screening plate.

2. An electron discharge tube according to claim 1 wherein the leads for the cathode comprise a coaxial pair of conductors, said coaxial pair of conductors comprising a metal tube sealed through the stem on which said pillars are mounted and a conductor coaxial with the tube insu-

lated therefrom and sealed therein by means of a glass bead seal.

3. An electron discharge tube in accordance with claim 1 including a guide member supported by at least some of said pillars and engaging said anode to locate the latter with respect to said grid element.

4. An electron discharge tube in accordance with claim 1 wherein the grid element comprises a pair of support rods attached to the apertured metal plate and grid wires extending between said support rods.

5. An electron discharge tube comprising an envelope, a grid support sealed into the envelope transversely thereof, a grid carried by said support, an anode on one side of said grid, a cathode on the other side thereof, a stem carrying a plurality of pillars, means attaching said grid support to said pillars, and an anode guide mounted on said pillars and engaging said anode to locate the latter with respect to said grid.

6. A lead-in conductor assembly for electron discharge devices, comprising a thin-walled metal tube with an external glass sealing area intermediate the ends of said tube, an electrode, adapted to be heated, attached to one end of said tube, said one end of the tube being hermetically closed, a solid rod of good heat conducting metal extending through said tube and in good heat transfer contact with said electrode and with the inside surface of said tube substantially throughout the length of said tube, said rod being out of contact with said tube opposite said glass sealing area.
